UNITED STATES PATENT OFFICE

168,476

HAT

Helene Rae, Winnetka, Ill., assignor to Rae-Gren,
Incorporated, Chicago, Ill.

Application February 21, 1952, Serial No. 18,615

Term of patent 7 years

(Cl. D3—13)

To all whom it may concern:

Be it known that I, Helene Rae, a citizen of the United States, residing at Winnetka, in the county of Cook and State of Illinois, have invented a new, original, and ornamental Design for a Hat, of which the following is a specification, reference being had to the accompanying drawing, forming a part thereof.

Fig. 1 is a front perspective view of a hat, showing my new design, and

Fig. 2 is a rear perspective view thereof.

I claim:

The ornamental design for a hat, substantially as shown.

HELENE RAE.
